US00D760733S

(12) United States Design Patent
Hwang et al.

(10) Patent No.: US D760,733 S
(45) Date of Patent:  *Jul. 5, 2016

(54) DISPLAY SCREEN OR PORTION THEREOF
WITH GRAPHICAL USER INTERFACE

(71) Applicant: Samsung Electronics Co., Ltd.,
Suwon-si, Gyeonggi-do (KR)

(72) Inventors: Woo-Seok Hwang, Seoul (KR);
Yong-Hwan Kwon, Sungnam-Si (KR)

(73) Assignee: SAMSUNG ELECTRONICS CO.,
LTD. (KR)

(*) Notice: This patent is subject to a terminal disclaimer.

() Term: 14 Years

(21) Appl. No.: 29/489,314

(22) Filed: Apr. 29, 2014

(30) Foreign Application Priority Data

Dec. 30, 2013 (KR) 30-2013-0066503

(51) LOC (10) Cl. 14-04

(52) U.S. Cl.

USPC D14/485

(57) CLAIM

The ornamental design for a display screen or portion thereof with graphical user interface, as shown and described.

DESCRIPTION

FIG. 1 is a front view of a display screen or portion thereof with graphical user interface, showing our new design; and, FIG. 2 is a front view thereof, as shown in a display screen environment. The broken line showing of the display screen forms no part of the claimed design. The broken lines are for environmental purposes only and form no part of the claimed design.
